(57) **CLAIM**

We claim the ornamental design for a walking frame, as shown and described.

DESCRIPTION

FIG. 1 is a front perspective view of a walking frame showing our new design.

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the drawings are for the purpose of illustrating portions of a walking frame and form no part of the claim.

1 Claim, 8 Drawing Sheets
